UNITED STATES PATENT OFFICE.

GEORGE LAWSON BALLARD, OF NORRISTOWN, PENNSYLVANIA, ASSIGNOR TO WILDMAN MFG. CO., OF NORRISTOWN, PENNSYLVANIA, A CORPORATION OF PENNSYLVANIA.

SPLIT-FOOT STOCKING-KNITTING MACHINE.

Application filed November 6, 1922. Serial No. 599,402.

The invention relates to the general type of machine which is designed to make split fabric goods, such for instance as split foot stockings, and it consists in the features and combination and arrangement of parts hereinafter described and particularly pointed out in the claims.

In the accompanying drawings—

Figure 1 is a front view of a knitting head embodying the invention.

Figure 1^a is a detail of a cam adjustment.

Fig. 2 is a side view looking from the left of Fig. 1.

Fig. 3 is a diagrammatic plan view. Figs. 15 3^a and 3^b are detail diagrams.

Fig. 4 is a developed view of the cam set looking from the outside inwardly. Fig. 4^a shows jacks.

Fig. 5 is a plan view of the needle circle 20 and the yarn feeds and associated parts, with the auxiliary yarn in feeding position.

Fig. 5^a is a view like Fig. 5, but of a fragmentary character, showing the instep yarn feed finger moved out from the needle circle 25 preparatory to being raised to take this yarn out of operation while the heel is being knit at the main feed.

Fig. 5^b is a view like Fig. 5^a, but with the instep yarn guide in raised position, this 30 being the stage in the operation following the condition illustrated in Fig. 5^a, the yarn remaining inactive but tied to the fabric ready to be introduced again when the knitting of the heel is finished and the knitting of the split fabric is to be resumed.

Fig. 6 is a diagrammatic perspective view indicating different positions of the instep yarn finger in relation to the needles.

Fig. 7 is a diagrammatic perspective view 40 showing the conditions when the instep yarn guide A is returned to feeding position after the heel is knit and the split fabric above the heel is to be knit.

Fig. 8 represents the condition at another 45 and more advanced period of the same stroke that is transpiring in Fig. 6.

Fig. 9 is a plan view showing the instep yarn feed finger in the raised position assumed by it when the split fabric has been 50 finished above the heel and the machine is about to go on round knitting with the main feed B alone.

Figs. 9^a and 9^b are diagrammatic side views of the needle row illustrating how the

instep yarn gets into the position shown in 55 Fig. 9 ready to be locked into the fabric with the main yarn and then severed and clamped within the needle row.

Fig. 10 is a diagrammatic view of the 60 stocking.

Fig. 10^a is a view of the fabric with its seams.

Fig. 11 is a detail view of pattern mechanism.

Fig. 11^a is an edge view of a pattern drum. 65 Fig. 12 shows discs, and Fig. 13 is a side view of part of the machine.

I have shown the invention as embodied in a machine of the type disclosed in Letters Patent of the United States granted to A. 70 M. Pigeon, No. 1,247,324 dated Nov. 20, 1917, and No. 1,266,044, May 14, 1918, though it will be understood that I do not limit my invention to its combination with any particular machine organization, but I 75 employ herein the Pigeon mechanism in part as a convenient means with which my improvements may be combined. It is also to be understood that the invention may be embodied in a latch needle machine, as well 80 as in a spring needle machine.

In the production of a split foot stocking, as is well known, the needle cylinder is oscillated and an additional yarn is thrown in at a point diametrically opposite the main yarn feed, so that the sole of the stocking is knit at the main knitting cams and main feed with one yarn, and the instep is knit with another yarn, at the additional feed, the suture between these two fabric portions occurring along each side of the foot of the stocking. 90

All of the needles throughout the circle in my invention, have butts at their lower portions, and the instep needles each have, 95 in addition to the low positioned butt, another butt at its upper portion, and each suture needle, at the end of the heel and toe series, has an upper butt which is shorter than the correspondingly located butts of the needles of the instep series. There are only two lengths of butts in the machine, viz, the two suture needles have their upper butts short and all the other butts, of all the needles, whether upper or lower butts, 100 are of the same length. The needles of the heel and toe series have no upper butts.

The machine has a main set of cams in-

cluding a pair of stitch cams 1, 1', Figs. 3 and 4, on each side of a center cam 2, radially movable switch cams 3, which direct the needle butts below the adjacent stitch cam 5 for knitting. These switch cams operate like those in the Pigeon machine. They are spring pressed inwardly towards the center of the machine, and they have laterally inclined faces 3^x so that in oscillating knitting 10 the butts of the needles on one stroke will pass along their normal path by striking these inclined faces, whereupon the switch cams will recede outwardly to allow the needles to pass, whereas on the other stroke 15 of the machine, the needles will be deflected downwardly to pass under the stitch cam. One of these switch cams is retracted by suitable connections for round knitting, as will be hereinafter described, these connections being like those of the Pigeon machine. 20

There is a needle raising cam 4 adjacent each stitch cam for restoring the needles to their normal plane after making the stitch, 25 and each of these raising cams has a guard cam 5 above it. In round knitting in clockwise direction, Figs. 3 and 4, only one of these main stitch cams 1, 1' is in service, for instance that numbered 1, all the needle butts being directed thereunder by the switch cam 3 belonging to this cam 1, these needles being restored to normal plane by the adjacent cam 4, and when restored the butts of these needles pass in this one plane 30 in the arrow direction X, all of the other cams including the switch cam 3, shown at the left of Fig. 4, this being a developed view from the outside looking towards the center of the machine, being out of service. 35

There is a narrowing pick 6 at each side of the main cam set as usual, and there is a double acting widening pick 7 arranged at the front of the machine pivotally mounted as will be described hereinafter to swing 40 laterally in either direction, and guided to move downwardly by a guide plate having inclines 8 against which the pick slides. 45

There are also levelling cams 7' for lowering any misplaced butts into the plane of 50 the widening pick.

For the additional yarn feed for making the instep portion of the stocking, there is an additional cam set at the front of the machine, which includes stitch cams 1^a, 1^b, 55 a central 2^a and restoring cams 4^a. The widening pick is arranged centrally of this additional cam set. All of the cams thus far mentioned, including the main and additional stitch cams 1, 1', and 1^a, 1^b, are arranged in the same horizontal plane. There 60 is also provided a pair of switch cams 3', 3'', elevated in respect to the cams before described, and located at the front of the machine. These switch cams are for directing 65 the instep needles and the suture needles,

i. e., those with upper butts, downwardly at certain times, as will be explained hereinafter, so that the lower butts thereof will be directed beneath the stitch cams 1^a, 1^b of the additional set for making stitches. These 70 switch cams are radially movable, as will be hereinafter described.

There are also two needle lifting cams 9, 9', which are elevated in respect to the stitch and associated cams. One of these lifting 75 cams, i. e., the one at the right, 9, performs the initial function of an instep cam, in that it raises the instep needles when reciprocating knitting for heel and toe work is to be performed, this being the cam at the right of 80 Fig. 4. Both of these cams 9, 9' come into use in making the split sole, but only the cam 9, when going onto the heel or toe work from round knitting. These two cams are 85 radially movable to and from the needle cylinder.

There is also an instep lowering cam 10, this also being radially adjustable, as will be described hereinafter.

When oscillating knitting for heel and toe work is to be performed, the needle elevating cams 9, 9' are set in towards the center of the machine where the cam 9, acting upon the upper butts a of the instep needles, these will be elevated to idle position and knitting 90 of the heel or of the toe will be proceeded with on the heel and toe needles which operate in connection with the main knitting cams 1, 1', and with the narrowing and widening picks 6 and 7, as in ordinary practice, it being understood that the picks and cams operate the suture needles at the end of the heel and toe series in just the same manner that the other needles of this series 100 are operated in forming heels and toes, because these needles having short upper butts, are not elevated to idle position by the cam 9, which is set in towards the needle cylinder only far enough to raise the instep needles 105 by engaging with the longer upper butts thereof, and Fig. 4 shows the upper butts, a, a² of these suture needles in dotted lines behind the cams 9, 9', and in their normal plane. Their lower butts a³ are in the same 110 plane with the butts of the heel and toe needles and can be picked in heel and toe knitting.

Where in this specification, "needle butts" are referred to, it will be understood that this is for convenience because the needles are driven by jacks which have the butts thereon, as shown in Fig. 4^a. 115 When the split foot is to be formed, the additional yarn is thrown into work by lowering the additional yarn finger A and the needle cylinder being oscillated, the following actions result. Each suture or seaming needle in passing the two yarn feeds will at one of these feeds, simply hold its loop, but will not form a new loop, while at the 120 other feed it will draw a new loop and cast 125

130

off the old. These effects will alternate in respect to the two feeds, thus, if we regard one of these suture needles, it will, on a clockwise stroke, miss loop forming and casting at the main yarn feed and will form a new loop and cast its old loop at the additional feed, whereas on the return or anti-clockwise stroke, this same seaming needle will not knit at the additional feed, but will 5 knit at the main feed. The actions in respect to the other suture needle will be the reverse of that just mentioned, i. e., on the clockwise stroke it will not knit at the additional feed, but will knit at the main feed, whereas 10 on the reverse or anti-clockwise stroke, this needle will miss knitting at the main feed and will knit at the additional feed. To express it in another way, the suture needle which leads a series of needles 15 on which stitches are to be formed, will simply hold its old loop on passing the stitch cam, as a lead needle, but this needle when passing the opposite stitch cam as a trailing needle, will draw a new loop and cast its old 20 loop.

At the main feed the leading suture needle is rendered inoperative for loop formation because it is picked up to elevated or inoperative position by the narrowing pick. This 25 needle, however, on passing the diametrically opposite or instep feed, or what I have called the second feed, will knit because the left hand switch cam 3'' will have been adjusted inwardly against the cylinder 30 prior to the arrival of the short butt suture needle which is now the trailing needle of those knitting at this feed. The switch cams 3', 3'' are mounted upon arms 11 and 11' respectively. These arms are pivoted at 35 12, 12' to sections 13 of a split collar, which sections are pivotally mounted at 13' to a suitable post extending up from the base of the machine. This collar forms a bearing 40 for the needle cylinder, and it may be opened 45 to allow access thereto. This also holds the jacks in their grooves. This split collar is indicated partly by dot and dash lines in Fig. 3. The arms 11, 11' are under tension 50 of springs 14 forcing them towards the center of the machine. The cam plates 3', 3'' are bevelled on their inner faces, as shown at 3^a in dotted lines in Fig. 3, and they are interconnected by a plate 15 which has notches 15^x receiving pins 16 projecting 55 up from the arms Figs. 3^a and 3^b. The plate 15 slides in a bracket 16^x. The notches of plate 15 are slightly wider than the diameter of the pins so that some lost motion exists, when one cam is operated, before this movement 60 is communicated to the companion cam, through the notched plate. It will be understood that these switch cams 3', 3'', 65 cooperate with the upper row of long butts a of the instep needles and at certain times, with the upper short butts a', a² of the seam

needles. The instep needles, as before stated, are raised by the instep cams 9, 9' engaging their upper butts, but these cams do not act on the upper short butts of the seam needles, as they are never set in close enough to the 70 needle cylinder to engage these short butts. This condition is illustrated in Fig. 4 in which the instep needles are in elevated position corresponding to their idle position in heel and toe work, but for split foot work, 75 these needles are operated to knit as well as the heel and toe needles.

Supposing the movement of the needles is in the arrow X direction, Fig. 4. The leading needle will be the short butt seaming 80 needle, whose upper butt is shown in dotted lines at a' back of the cam 9, this needle having assumed its normal plane. On this stroke, the cam 3' will be swung out by the upper butts of the instep needles contacting 85 with the tapered or bevelled inner face 3^a of this cam, see plan view Fig. 3^a. The swinging of this cam out to the position shown in Fig. 3^b, will, because of the plate 15 and pins 16 connecting the two arms 11 90 and 11', cause the arm 11' to be swung out also, but not as far as the arm 11, see Fig. 3^b, this difference being due to the lost motion in the notches 15^x of the plate 15. The cam 3'' will therefore stand far enough away 95 from the needle cylinder that the short butt a' of the leading needle a, this being one of the seaming needles, will pass this cam without being switched down thereby, and its lower butt will not be brought into line with 100 the stitch cam 1^b, and hence on this clockwise stroke this needle will not form a new loop, but will hold its old loop and pass the cam in normal position. The instep needles will go down at this time, i. e., as they pass the 105 cam 3'', as their upper butts are long enough to engage the inclined lower edge of the said cam, as indicated in the dotted lines in Fig. 3^b.

The trailing seaming needle a², when this 110 comes around on this stroke, will form a loop because as soon as the last normal butt instep needle a² passes the cam 3', the spring 14 will snap this cam towards the center of the machine, whereupon it will rest momentarily upon the short butt trailing needle a², 115 but as soon as this passes away from the end of the cam 3' the latter will take another quick step movement inward and thus the plate 15 will move inwardly and allow the 120 cam 3'' to move inwardly also under tension of spring 14, and as this movement takes place, the cams snap all the way in towards the cylinder, and as this happens before the short butt needle a² reaches the inclined under edge of the cam 3'', the latter will cause 125 the downward movement of the short butt needle and thus cause its lower butt to engage the stitch cam 1^b for making a stitch. It may be pointed out here, however, as will 130

be clear from Fig. 4, that the movement of the needle a^2 to the left is to be regarded as the leading needle as it comes around towards the stitch cam 1 of the main set and it is rendered inoperative as to forming a new loop at this feed because it is picked up to what corresponds to idle level $y-y$ in heel and toe knitting, by the narrowing pick 6 shown at the left of Fig. 4, and having thus joined the elevated needles as the trailing one of those which will knit at the cam 1^b of the additional cam set, it will, as just stated, form a loop at this cam 1^b.

The needle cylinder makes substantially a complete revolution at each stroke, and each seaming needle a' or a^2 passes both the main feed and the additional or instep yarn feed at each stroke. Each seaming needle makes a loop at one feed, but does not make a loop at the other feed on each stroke. Considering one of these needles, it will be understood that on one stroke it will not make a loop at the main feed, but will at the second or instep yarn feed, whereas on the return stroke, it will not make a loop at the second feed, but will at the main feed, and it will be understood that both suture needles make their loops at the same time in the strokes and miss loop formation at the same time in the strokes.

On the stroke opposite to that of the arrow in Fig. 4, it will be understood that the needle a^2 will not knit in passing the auxiliary stitch cam 1^a, as it will not be thrown down by the switch cam 3', but it will knit at the main stitch cam 1', the switch cam 3 being controlled to be set inward towards the needle cylinder for deflecting the needle downwardly to pass under this stitch cam. The needle, a' on this stroke, which is the reverse of that indicated by the arrow X, will not knit at the main feed (stitch cam 1' because it will be picked up to the elevated plane $y-y$ by the narrowing pick shown at the right of Fig. 4), but on arriving at the auxiliary feed A, it will knit because it will then be the trailing needle of the series that are knitting at this feed, i. e., it will pass switch cam 3'' and be switched down by cam 3' when this snaps close against the cylinder because of the cam 3'' snapping off from this trailing needle. It will thus be seen that each of the suture needles knits at one and does not knit at the other feed on each stroke, it missing knitting when it leads and knits when it trails the series, and that on the return stroke it alternates the above order, missing knitting at the feed which it knitted at on the first stroke, and knitting at the feed where it missed knitting, and as to the other short butt needle, this knits and does not knit in like manner with the short butt needle first mentioned.

During round knitting, or during heel and

toe work, the switch cams 3', 3'' are held out of action, i. e., away from the path of the upper needle butts by a lever 17 pivoted at 18 to the bracket 16^x in which the slide 15 moves, the lever engaging a pin 20 on the under side of the slide 15, on which also a spring 21 bears to force the slide inwardly. The lever 17 is operated to retract the slide by a rod 22 extending to a lever 23, connected by a rod 24 to any suitable form of controller, which is combined with the Pigeon organization. This connection is operated automatically and the cams are allowed to set themselves outwardly away from the needle cylinder to inoperative position by a spring 25 and they are forced into operative position by the pattern wheel 26 which is fixed on the pattern drum shaft 27 of the Pigeon machine, said pattern wheel as shown in Fig. 11 having raised portions 28, 29 to lift the lever 30 connected with the rod 24, for setting the switch cams into action. The lever 30 is pivoted at 31 to a suitable part of the frame.

The widening pick is swivelled, having vertical swinging movement about pivot 7'' in a standard 7^x which turns in a bearing in a lever 32 pivoted at 33 to the base of the knitting head, which lever is operated by a rod 34, lever 35 and rod 36 controlled by a spring 37, Fig. 11 to force the pick inwardly towards the cylinder for picking the needles and, by a lever 38 pivoted at 31 and operated on by the pattern wheel 26, which has parts 39, 40, 41 for lifting the lever 38 to set the pick out away from the path of the needle butts.

The levers 30 and 38 are also controlled by a pin 42 on a swinging rod 43 pivoted to a suitable part of the machine frame at 44. This rod is connected by a pin 45 set therein, which enters a slot in a link 46 which is connected with an arm 47 pivoted to the frame at 48 and controlled by a cam portion 49, dotted lines, Fig. 11 on the pattern wheel 26. A spring 46' connected to the link and the pin 45 tends to pull the hanging rod 43 towards the right. The hanging rod is moved leftward by a pin 42' on the quadrant 42'' pivoted at 42^x, this quadrant being substantially that shown in the Pigeon patent. It presses the hanging rod leftward at each backward stroke, i. e., to the left in Fig. 11.

This employment of the quadrant to exert control on the levers 30, 38 is for the purpose of exercising said control at such time as is necessary while the pattern wheel 26 is not in forward motion in the direction of the arrow. It will be understood that the pattern wheel moves step by step by a pawl operating a ratchet wheel on shaft 27, the operation of which is controlled by a pattern chain. The mechanism described will permit an automatic change to take

place when the pattern wheel is at rest, or in other words, when the backward movement of the pawl takes place.

As above stated, the levers 30, 38 are moved upward by the projections on the pattern wheel to move the switch cams 3', 3'' in towards the needle cylinder and the widening pick out or away from the needle cylinder. The fall of these levers 30, 38 i. e., at their forward ends is controlled, after the pattern wheel has moved forward to remove its projections from under these levers, by the position of the pin 42. This pin at times overlies the rear ends of the levers and holds them from falling until such time that the quadrant on its rear stroke brings its pin 42' against hanger rod 43 and moves pin 42 to the rear which allows the levers 30, 38 to drop, thus allowing the switch cams to move out to inoperative position, and the widening pick to operative position, and this action takes place at a later period than the forward movement of the pattern wheel 26.

After the next forward movement of the pattern wheel the lever 47 drops off of the pattern block 47' and this throws the detent or hanger bar 43 to the left out of operation.

The Pigeon machine has a series of fingers connected to a bar 50, Figs. 1 and 3, which is carried by a bracket 51 fixed to a rod 52, which slides axially when the clutch is thrown for changing from round to reciprocating knitting, or the reverse, and this shifting movement, carries the fingers towards or from the needle cylinder as the case may be. When the machine automatically sets itself for round knitting the finger 53 will retract the switch cam 3 at left or Fig. 4, see also Fig. 3, and the finger 54 will throw one of the narrowing picks 6 out of operative position, i. e., the left hand one of Figs. 3 and 4, see also Fig. 2, the end of this finger bearing against a pin 6' extending up from this pick. This bar 50 in my organization also carries a finger 55 connected by a pin 56 to a slide 57 guided by its slot 58 engaging a pin 59 extending down from one of the sections of the collar 13, and this slide at its inner end carries the instep lowering cam 10 which lowers the instep needles when the machine is to go on round knitting.

The finger 54 is utilized for positioning the instep or raising cams 9, 9', and for this purpose it has a pin 61 engaging an arm 62, Fig. 3 pivoted at 63 and bearing on a pin 64 on the tail 65 of the arm 66, which is pivoted at 67 to the collar section 13 and carries the needle raising cam 9'. The tail 65 is connected by a link 68 with a cross arm 69 pivoted at 13', which by another link 71 connects with the tail 72 of the arm 73 pivoted at 74 to the collar section 13, and the other raising cam 9 is carried by the latter arm. The arm 66 which carries the instep

cam 9' is pressed inwardly by a spring 60*, which pressure is transmitted through the connections to the other arm 73 of the cam 9. Both of these arms are limited in their inward movement by stop pins 9* and this 70 limits the inward positions of the cams 9, 9', so that while they will engage the needles having the longer upper butts, they will not engage the short upper butts of the seam needles. 75

The collar sections 13, which are also pivoted at 13', extend around the cylinder and at their front ends are bifurcated to embrace posts 74 extending up from the base of the head, and these sections 13 are held locked 80 to these posts by nuts 75 threaded on the posts and having conical portions 76 which engage seats in the bifurcated ends of the arms 13 to hold them in place. By loosening the nuts 75, the arms 13 can be swung 85 aside carrying with them the arms 11, 11' with their cams 3', 3'', and also the arms 66 and 73 with their cams 9, 9'. The arm 73 can be swung out independently, it being pressed by a spring 76'. This arm is jointed 90 with its tail portion 72 at 77 so that it can be swung out by hand independently of its tail portion, but can also be swung out automatically when its tail portion is drawn towards the center of the machine. 95

Auxiliary yarn control.

For making the split foot, the auxiliary or instep yarn is thrown in at the feeding point diametrically opposite the main feed and the machine being now in oscillation, the split foot will be formed, the instep yarn remaining in work until the heel is to be formed, whereupon the following actions take place. The heel yarn may be changed. 100 The instep or auxiliary yarn feed finger A is first moved radially outward from its feeding position close to the circle of needles, so as to remove the instep yarn from the needles. Compare in this connection, the 110 feeding position of the yarn finger A in Fig. 2 with this outward position in Figs. 5^a and 6. In the latter figure the finger A is shown in its feeding position in full lines and in its outward position in dotted lines. Also 115 the elevated position of the yarn feed finger is indicated in this figure with the yarn in dotted lines extending from said finger to the point where it is tied to the fabric. The yarn when lifted out of work, does not wrap 120 around any needle, but passes clear to the interior of the needle row. For thus operating the yarn finger A the block 78 to which the instep yarn finger is pivotally mounted at 78', is swung on its pivot by the 125 rod 78" connected with the post 78^a extending up from the base plate of the yarn finger block. This block is pivoted to the center shear and clamp supporting plate 80" at 78^b, and swings horizontally. The rod 78" 130

is operated by the supplemental pattern drum 79, Fig. 2, which is generally similar to that used in the Pigeon machine for operating the yarn fingers of the main feed. Said rod is connected with a lever 79' pivoted at 79" to the bracket 79^a, the lower end of the lever resting on the supplemental pattern drum and a spring 79^b connected with the bent end of the rod serves to keep the lever in contact with the pattern drum. Movement of this rod to the right, Figs. 2 and 5, will swing the yarn finger block to the right and move the instep yarn feed finger A outwardly from the needles Fig. 5^a, and then the said yarn finger will be raised and as its arc of movement is inward in respect to the needle circle the yarn will be carried between the needles and will extend directly from the fabric upwardly and inwardly of the needle circle, as shown in dotted lines in Fig. 6, and then as the needles continue to move in the clockwise direction this yarn will be directed under the guide or guard plate 80, and will be directed into the slot 80' in the front of the base plate 80" and beyond the spring detent 80^a in which position it will be held during the entire operation of knitting the heel with the needle cylinder in oscillation. This yarn will not be cut but will remain tied into the fabric. It will extend through the slot 80' and beneath the plate 80" and beneath the level of the cutter 80" so that it will not be severed, but will be allowed to float. In lifting the yarn out of action as just described, the yarn finger is so timed in its rising movement that as soon as the point where the yarn is tied into the fabric comes to position in the same radial plane passing through the yarn guide eye, the upward movement takes place to move the yarn from outside to inside the needle row, and this takes place without wrapping the yarn at all across or around any needle shank. Fig. 5^b indicates at v the condition soon after the yarn is lifted up. It extends from the yarn finger directly to the point where it is tied into the fabric. At v' I show a full line indication of the position of this yarn after the tie point t has progressed in the clockwise arrow direction to the position t'. Now the yarn has been directed into the slot in the plate 80" and will be retained therein by the detent spring while the needle circle oscillates. When the heel pocket is finished and the split portion of the stocking above the heel pocket at the back of the stocking is to be knit, that is the portion corresponding in location to what is known as the high splice, together with the part above the instep, the instep yarn finger is again thrown into work and oscillating knitting continues the same as for the formation of the split foot. Fig. 7 shows the position of the yarn fin-

ger A when it has been returned to feeding position, as just stated, after the formation of the heel and with its end tied into the fabric at the end of the heel gore. It will be noticed from this figure that the timing of this throwing in of the instep yarn again is such that it will pass between, say the fourth and fifth needles from the end of the row, which will knit on this stroke (clockwise) and as this stroke continues, the 70 yarn will wrap around the outside of the needle row, see Fig. 8 and here it will be noticed that this instep yarn will be knit into the fabric with the main yarn going in from the main yarn finger B. This 75 knitting in of these two yarns jointly will take place at the right hand stitch cam 1 of the main set, and Figs. 7 and 8 illustrate this, and Fig. 8 illustrates also that a short length or bow of this instep yarn will be 80 left at z extending from the point where the end of this yarn is tied to the fabric, to the point where it is knitted in at the fourth or fifth needle, as the case may be. This bow appears of course, on the inside 85 of the fabric. This instep yarn having been 90 knit into the section of the split fabric above the heel, that is, that section which is knit with the main yarn from finger B and thus having been locked in place, the anti-clockwise stroke takes place and the length of 95 yarn which is wrapped around the outside of the column of idle needles, see Fig. 8, will be taken up by the yarn take-up mechanism and thus drawn back through the feed finger A. On the next clockwise stroke this 100 instep yarn will proceed to make that portion of the split fabric around the front of the ankle, and this will take place first at the left hand knitting cam 1^b of the front 105 or second set of cams, and then at the right hand cam 1^a on the next anti-clockwise stroke, and so on. While these actions are taking place, the portion above the heel will be knit by the main set of cams and the 110 heel and toe needles at the main feed B.

It will be understood, of course, that up to this time, following the completion of the heel and while the first clockwise stroke is taking place, as shown in Figs. 7 and 8, the front or second set of cams are inoperative because the switch cams 3', 3" have been retracted away from the needle butt path.

This locking in of the instep yarn takes place substantially at the point z' as indicated in the diagram of the stocking.

The auxiliary or instep yarn finger, when feeding, at all times lies just outside the needle row. The split fabric portion above the heel pocket having been knit, as just described, the instep yarn guide is lifted by the pattern drum from its feeding position to that shown in Figs. 9, 9^a. In this lifting action, the auxiliary yarn feed finger is not given first a radial outward move- 130

ment as in the case above described when beginning to knit the heel, as now it is not intended to leave this yarn tied into the fabric, until it is brought into work again, 5 but it is intended to sever and clamp it within the needle circle. It is also intended, however, to lock it into the upper edge of that portion of the split fabric which lies above the heel by knitting it in together 10 with the main yarn and this is the action taking place in Fig. 9. In the diagram of the stocking, the shaded portions are those knit with the cotton yarn throughout the foot and above the heel, and the portion 15 shows the silk or other instep yarn, and the line of stitches where the instep yarn is locked into the dark portion of the split fabric, is indicated at z^2 .

In this lifting action just mentioned, the 20 yarn finger is raised directly from its feeding position, as indicated in Fig. 9^b, and it will lay first over some of the beards and as the movement continues clockwise, the 25 yarn will pass in between the needles at some distance back from the travelling point where it is tied into the fabric and this stretch of yarn will lay against the outer side of the stems and under the beards and will be in position to be taken by these 30 beards when the main stitch cam 1 is reached Figs. 4 and 9, and knit and locked into the fabric with the main yarn and Fig. 10 shows where this locking effect takes place, viz., at z^2 , as above stated. In performing the 35 action the yarn extending from the raised yarn finger to the fabric lays on the outside of the needles and it will ride over the upper edge of the guide-plate 80, as shown in Fig. 9^a, and will be directed to the hook 81 which 40 will catch the yarn on the inside of the needle row, and from there the yarn will extend out between the needles and along the outside of the stems of the few mentioned see z^3 to z^4 , Fig. 9, to be knit in as 45 above described. The continued movement in a clockwise direction will cause this yarn to be carried under a spring wire clamp 82 and then to a cutter 80^b at the edge of the notch 83 in the base plate 80^a where the 50 yarn will be severed, but the cut end will be held under the clamp until this clamp is relieved from pressure and releases the yarn.

As before stated, the instep yarn finger is 55 pivotally mounted at 78'. It has a bifurcated base portion through the depending ends of which the pivot extends and it is pressed by a spring 84 which tends constantly to move the yarn finger to its lowered position. If is operated by a rod 84' 60 extending from the upstanding ear 84'' of its base portion to a lever 84^a which is pivoted at 79'' and has its lower end resting on the supplemental pattern drum 79, which has high and low parts disposed about it by 65 which the lever is operated.

The main yarn fingers are pivotally mounted at 85 and are normally pressed down by springs, one of which is shown at 85'. The main yarn fingers are raised to inoperative position by arms 85'' pivotally mounted, and having downward extensions operated by the supplemental pattern drum, substantially as in the Pigeon patent. When lifted out of work, the main yarns are carried beneath a clamp 85^a and a shear blade 75 85^b, which latter severs them, and the cut ends are held by the said clamp.

This clamp and shear blade are both operated by a vertically extending rod, spring 86 pressed downwardly as at 86, and raised by 80 a lever 86' bearing on the underside of pin 86^c operated by a rod 86'' extending to a lever 86^a at the supplemental pattern drum, Fig. 2. The spring pressed plunger or rod 86, is connected by a pin 86^b with the movable shear blade 85^b which is pivoted to the standard at 87 and a second pin 86^d connects the vertically working plunger with the clamp 85^a so that both will be lifted when the plunger is raised to allow the yarn to pass beneath them, and thereupon they both fall together to sever and clamp the 90 yarn.

In Figs. 2 and 9, I show an arm or finger 95 88 extending near the instep yarn guide. This will catch the yarn as it is raised out of work and assist in directing it as shown in this Fig. 9. This finger is an extension of the bearing 88' for the spring clamp 82. This bearing is carried by a lever 88'' pivoted to the post 89 extending up from the shear and clamp plate and this lever is operated by a rod 90 extending back to a lever 90' at the supplemental pattern mechanism to be operated thereby to lift the bearing 100 105 and thus raise the spring wire clamp 82 to release the instep yarn.

Referring to Fig. 12, this shows certain of the members of the pattern drum 79 in their 110 positions relative to the same vertical line. The disc or member marked 1st, is the same one shown in Fig. 2. It has high and low parts, and when the lever controlled by it rides on any part of the high periphery, the yarn finger A will be in its elevated or non-feeding position, shown in dotted lines in Fig. 2, and when the controlling lever rests upon the low part of the cam, the yarn finger A will be down. The disc marked 2nd, 115 is the one for controlling the radial position of the yarn finger A, i. e., whether close to or removed from the needle row. It controls parts 78'', 78^a and 78 to secure the radial position of the finger A, as just mentioned. When the notch in this disc is in 120 position to allow the controlling connection or lever to drop therein, the yarn guide A will be thrown outward radially to its outermost position, but when the connection, or the lever, rides on the concentric, or main 125 130

part of the periphery, then the yarn finger A will be held in its normal position close to the needle row.

The disc marked 3rd, controls the wire clamp 82. When its controlling lever drops in the notch shown in this disc, the wire clamp is lifted, but when the high concentric periphery is active against the connection leading to the wire clamp, the said clamp will be held in clamping position.

The disc marked 4th, is the one for controlling the shear blade 85^b and clamp 85^a, and it has eight teeth for this purpose, each tooth representing one shearing action.

15 All of these discs are keyed to a drum or shaft. The same drum carries other discs for operating the main yarn fingers, substantially as in the Pigeon machine, and it has been thought unnecessary to show these 20 discs.

The drum 79, or the discs comprising this drum, are operated through any suitable mechanism. I show in Fig. 13, one form of mechanism driven from the usual elements 25 of the Pigeon machine. In this figure, 91 indicates a gear (marked 35 in Pigeon Patent No. 1,266,044), this being the gear which operates the pitman which operates the quadrant of the said machine. On the shaft 30 of this gear wheel is fixed a cam 92 operating a lever 93 pivoted at 94 and having a pin 95 to engage, at certain times, a notch 96 in a link 97. The link operates a pawl carrying arm or lever 98, turnable about the 35 axis of the drum 79 and having a pawl 99 to operate a ratchet wheel 100 fixed on the shaft of the drum. The link 97 is controlled in its relation to the pin 95, which actuates it by a pin 105 on an arm or lever 40 101 on a shaft 102, which has an arm 103 depending therefrom to be operated by suitably spaced lugs on the pattern chain 104, forming a part of the usual Pigeon organization. This pattern chain passes 45 over a wheel on the shaft of the pattern drum, as usual in the Pigeon machine, this shaft being marked 27 herein, and 73 in the said Pigeon patent. The arms 101 and 103 are pressed by a spring 104' to hold the 50 link 97 out of the path of the pin 95. When the pattern chain calls for it, the arms 103 and 101 are operated to allow the link 97 to move towards the right under tension of the spring 106, so as to make the pin 95 engage the notch 96 on its downward stroke, and thus pull the link 97 down to advance 55 the drum 79 one step by means of the pawl and ratchet. The pawl will be returned to normal position by a spring 107. 60 A stop pin 108 determines the retracted position of the pawl. The pawl arm has a handle 109 by which it may be operated by hand.

Where I refer to a main yarn feed, this of course, is used in a generic sense to include

any desired number of yarn fingers at this feed for supplying a yarn for heel and toe and leg work, or for making yarn changes as may be desired.

The stocking is knit by beginning at the toe, then knitting in order the toe pocket, the ring toe portion, split foot, heel, split fabric section around the ankle, and then the leg. This enables me to lock the instep 70 yarn into the fabric at the top of the heel or 75 at the top of the split fabric section when the silk or instep yarn is about to be taken out of work. This is done, as before stated, by carrying this end around to the main yarn feed and knitting it in with the main yarn. 80 This locking effect could not be secured if the stocking were knit by finishing at the toe.

Fabric.

85

Considering the dark loops as those knit with the main yarn at the main feed and the light loops as those knit with the instep yarn at the additional feed, it will be seen that along the seam or suture S—S there 90 appears a light loop s at every other course, alternating with dark loops s' , and these dark loops appear at every other course of the sole fabric. These alternate light and dark loops jointly form a continuous wale 95 at the seam.

It will be noticed also that the sinker wale s^2 between any one of the light loops and the next light loop formed with the continuation of the light yarn as at s^3 , and 100 which is a part of the next wale and next course, will extend at an inclination from the light suture loop to the next light loop (s^3) formed in the standing wale adjacent 105 to the suture. This formation gives a structure in which the light yarn instep fabric has loop s along the seam lying within the general dimensions of the sole fabric and conversely the dark seam loops s' of the sole 110 fabric extend or overlap into the general dimensions of the instep fabric. The sinker loops of the dark yarn as at s^4 , which extend from the dark suture loops s' to the next loop formed of a continuation of this 115 yarn, like the yarn s^2 of the sinker wale of the light yarn, also extends at an inclination, but in the opposite direction to the light sinker loop s^2 , because the next loop formed after any dark suture loop is in the adjacent wale (to the right) but in the next course, i. e., see the loop s^5 . The suture S'—S' is 120 formed in a manner similar to that above described, but its light and dark suture loops are in alternate courses for those of the seam S—S.

This structure gives a perfectly flat seam and of the same thickness as the rest of the fabric. There are no superfluous or extra loops, all loops being single. This is due to 130 the organization of the machine whereby

125

120

125

130

each seaming needle will make a stitch on one side of the fabric, but not on the other side, this being true of both seaming needles so that no extra loop is formed. To state the 5 operation in another way, while each seaming needle passes both feeds on each stroke of the machine in one direction, it will form a loop at only one of these feeds, i. e., that feed where it is the trailing needle of those which 10 are to knit. The suture needles deal with single loops. They never form, carry or cast off any but single loops.

It may be noted that in Fig. 3 I have not indicated the collar sections 13 in full line 15 throughout, but have indicated the inner margin of this only by a dot and dash line. This is for convenience of illustration, as in view of the fact that these collar sections are in a higher plane than the various cams, 20 these cams would be hidden if the collar sections were shown complete both as to their outer and inner margins.

The method and article herein described will be made the subject matter of a divisional application.

I claim—

1. In combination in a split foot stocking knitting machine, a main feed for heel and toe yarn, a second feed for instep yarn 30 and means for causing the shifting of the instep yarn at a prescribed period of the knitting to the main feeding point to be knit into the fabric with the main yarn at said main feeding point, substantially as 35 described.

2. In combination in a split foot stocking knitting machine, a main feed for heel and toe yarn, a second feed for instep yarn and means for causing the shifting of the instep 40 yarn at a prescribed period of the knitting to the main feeding point to be there knit into the fabric with the main yarn, and thereafter continue knitting with said instep yarn at said second feed for making the front 45 section of the split fabric at the ankle while the rear section of said split fabric is made by the main yarn, substantially as described.

3. In combination in a split foot stocking machine, a main feed for heel and toe yarn, 50 a feed for instep yarn including a guide for said yarn, and means for operating said guide to lift the yarn out of work for heel and toe work and for throwing said yarn into work to be knit in first at the main yarn 55 knitting point with the main yarn and thereafter continued at the knitting point for the instep yarn, for making the front section of the split fabric at the ankle while the rear section of said split fabric is made by the main yarn substantially as described.

4. In combination in a split foot stocking machine, a main feed for heel and toe yarn, 60 a feed for instep yarn including a guide for said yarn, and means for operating said guide to lift the yarn out of work for heel

and toe work and for throwing said yarn into work to be knit in first at the main yarn knitting point together with the main yarn and thereafter continued at the knitting point for the instep yarn for making the 70 front ankle portion of the split fabric, said instep yarn remaining tied to the fabric when out of work during the knitting of the heel, substantially as described.

5. In combination in a split foot stocking 75 machine, a main feed for heel and toe yarn, a feed for instep yarn including a guide for said yarn, and means for operating said guide to lift the yarn out of work for heel and toe work and for throwing said yarn 80 into work to be knit in first at the main yarn knitting point jointly with said main yarn and thereafter continued at the knitting point for the instep yarn for making the front ankle portion of the split fabric, 85 said instep yarn remaining tied to the fabric when out of work during the knitting of the heel, and when locked into the fabric with the main yarn, there being formed a bow of this yarn extending from the tied end to the 90 point where this yarn is locked in the fabric, substantially as described.

6. In a split foot stocking knitting machine, the combination of a main feed for heel and toe knitting, a second feed for knitting 95 with an instep yarn, including a guide for said yarn, means for operating the guide to withdraw the instep yarn from work while its end remains tied into the fabric and introducing a portion thereof intermediate the tied end and the guide to a few of the needles to be knit in at the main feed jointly with the main yarn, while said end remains tied to the fabric, and thereafter continuing said knitting in of the said 100 instep yarn at the second feed on reverse stroke of the needle carrier, substantially as 105 described.

7. In combination in a knitting machine 110 for making split foot stockings, a main yarn feed for heel and toe work, a second yarn feed including a movable guide for the instep yarn, and means for controlling said guide to lift the yarn out of work by moving it to the interior of the needle circle while 115 its end remains tied to the fabric and while the heel is being knit and thereafter moving said guide to carry the said instep yarn between the needles to the outside and allow it to wrap about the circle of needles until 120 the main knitting cam is reached where said yarn is knit in jointly with the main yarn, the yarn guide for the instep yarn then remaining in feeding position to continue knitting of this yarn at the second feed on the 125 reverse stroke of the needle circle, substantially as described.

8. In combination in a split foot stocking 130 knitting machine a main yarn feed for heel and toe and leg work, an instep yarn feed,

a guide for placing said instep yarn feed in action for knitting the instep while the sole is being knit at the other feed, means for controlling the guide to withdraw said guide 5 from action while the heel is being knit and while the end of the instep yarn remains tied into the fabric, then to introduce said instep yarn feed again for locking the instep yarn jointly with the main yarn in the fabric, 10 then to continue the knitting of the portion over the ankle with said instep yarn while the portion above the heel is knit with the main yarn and then to remove said instep yarn guide from operative position, and to 15 cause the instep yarn to be first locked into the fabric with the main yarn and then severed and the end clamped for making the next stocking, substantially as described.

9. In combination in a split foot stocking 20 machine, a main yarn feed with a cam set for making the sole and heel, and portion above the heel, a second yarn feed for the instep yarn with a cam set for making the instep and portion at the front of the ankle, 25 a yarn guide at the second feed and means for positioning it at the outside of the needle row for feeding the yarn to the needles, for moving it outwardly from the needle row and thereafter inwardly across the needle 30 row whereby the yarn will be located within the needle row without being caught by any needle and with its end tied to the fabric, and for thereafter returning the yarn guide to feeding position, all of said movements 35 taking place while the knitting cams at the second feed are out of service on the needles, the yarn thereby being extended between the needles and wrapping around the needle circle and carried to the main knitting cams 40 to be there knit into the fabric jointly with the main yarn.

10. In combination in a split foot stocking machine, a main feed with a cam set therefor, a second feed for the instep yarn 45 with a cam set therefor, and a yarn guide for the instep yarn pivoted within the circle of needles with means for shifting it from feeding position outside the needle row to a position within the needle row and back 50 to its feeding point again, substantially as described.

11. In combination in a split foot stocking machine, a feed for the instep yarn with a cam set therefor, and a yarn guide 55 for the instep yarn with means for shifting it from feeding position outside the needle row to a position within the needle row and back to its feeding point again, said shifting means including a shifting support 60 within the circle of needles on which the yarn guide is pivotally supported, means for shifting the support and means for swinging the guide up and down, substantially as described.

12. In combination in a split foot stocking

knitting machine, a feed for the instep yarn having a cam set therefor and a movable instep yarn guide, cutter and clamp means for the instep yarn within the needle circle, a deflector for the instep yarn within the needle circle, and means for operating the instep yarn guide to inoperative position when the heel is to be knit and for then causing the deflector to deflect said yarn away from the cutter and clamp and for operating the 75 said instep yarn guide to inoperative position when the knitting of split fabric above the heel is terminated and for then causing the deflector to deflect the instep yarn to the cutter and clamp, substantially as described. 80

13. In combination in a split foot stocking knitting machine, a feed for the instep yarn with a needle operating cam set therefor, a movable yarn guide for the instep 85 yarn, a cutter and clamp for the instep yarn within the needle circle, a deflector for the instep yarn fixed within the needle circle and means for giving the instep yarn guide varying movements in withdrawing the yarn from work respectively when the heel is to 90 be knit and when the section of the split fabric above the heel is to be terminated, the said deflector deflecting the instep yarn from the cutter and clamp when the heel is to be knit and directing the instep yarn to said 95 cutter and clamp when the knitting of said split fabric section is terminated, substantially as described.

14. In a split foot stocking machine, the combination of a main yarn guide, an instep 100 yarn guide at substantially opposite sides of the machine, a needle operating cam set adjacent each guide, means for moving the instep yarn guide from its feeding position outside the needle row, across the said row, at a point a few needles in rear of the point where the yarn is tied into the fabric, so that the yarn will lay along a few of the needles to be knit in thereby, with the main yarn, when said needles reach the 110 stitch cam of the main set, and means within the needle circle for cutting and clamping the end of the instep yarn until the instep 115 yarn guide is shifted outwardly across the needle row to its feeding position outside said row, substantially as described.

15. In combination in a split foot stocking machine, a main yarn feed, a cam set for operating the needles adjacent thereto, 120 an instep yarn guide, a needle operating cam set adjacent said guide, means for shifting the instep guide from its feeding position outside the needle row to idle position at a point elevated within the needle row, and with the yarn temporarily lying across the outside of the beards of several of the needles, in advance of the point where the yarn passes between the needles, and a deflecting member or guard inside the needle 125 row for directing the yarn upwardly at 130

that portion which lies between the instep 5
yarn guide and the point where the yarn
is tied to the fabric, said instep yarn at
the several needles being knit into the fab-
ric at the main feed with the main yarn,
and a clamp and cutter to which the in-
step yarn is directed, so that it will be sev-
ered and its end held within the needle row
10 to be reintroduced to the needles when said
instep yarn guide is again moved to its
feeding position.

16. In combination in a split foot stock-
ing machine, a guide for the instep yarn,
cam means for shifting the instep yarn
15 guide from its feeding position outside the
needle row to an elevated position inside
the needle row, a deflecting member for mov-
ing the yarn upwardly at a point between
the instep yarn guide and the end of said
20 yarn, a fixed bearing within the needle circle
against which the elevated yarn bears, and
a clamp and cutter within the needle circle
for severing the said instep yarn, and hold-
ing its end, substantially as described.

25. 17. In combination in a split foot stock-
ing knitting machine, a plurality of main
yarn guide fingers, a clamp and cutter within
the needle row for cutting the yarn and
holding the end when yarn changing takes
30 place, a supplemental cutter and clamp within
the needle circle, a guide for the instep
yarn, means for shifting said guide from a
position outside the needle row to a position
inside the said row, and means for direct-
35 ing the instep yarn when its guide is shifted
at times to idle position on the inside of
the needle row, to the supplemental cutter
and clamp, and at other times away from
said cutter and clamp substantially as de-
40 scribed.

45. 18. In combination in a split foot stock-
ing machine, a guide for the instep yarn
with a needle operating cam set therefor,
means for shifting the instep yarn guide
from a feeding position outside the needle
50 row to a position inside the needle row, a
cutter and clamp within the needle row, and
a deflecting member for deflecting the in-
step yarn upwardly and downwardly within
the needle row, the said shifting means
55 for the instep yarn guide giving the same
a variable movement, so that in one case
the yarn when withdrawn from work will
be deflected upwardly and directed to the
clamp and cutter, and in the other case, the
yarn when withdrawn from work will be di-
rected downwardly to avoid the said clamp
and cutter, and to maintain its connection
with the fabric, substantially as described.

60. 19. In combination in a split foot stock-
ing knitting machine, heel and toe needles,
instep needles, and suture needles, said suture
needles having short upper butts, the
instep needles having upper butts longer
65 than the upper butts of the suture needles,

all the needles having lower butts, needle
operating cams and picks, cooperating with
the lower butts, and switch cams cooperat-
ing with the short butt suture needles to de-
press them to the knitting cams for said suture
needles, substantially as described. 70

20. In combination in a split foot stock-
ing machine, a set of knitting cams for the
heel and toe needles, a second set of knitting
cams for the instep and suture needles, ar-
ranged at the same level with the first set of
cams, instep cams at a higher level and
switch cams for throwing the suture needles
down to the second set of knitting cams,
and arranged at a higher level than the 80
knitting cams, instep, heel and toe and suture
needles having lower butts, said instep and
suture needles having upper butts sub-
stantially as described. 75

21. In combination in a split foot stocking 85
machine, a series of instep needles, a series
of heel and toe needles, a single suture needle
between the series of instep needles and the
series of heel and toe needles at each side
of the needle circle, said suture needles each 90
having upper and lower butts, a main feed
at which the toe, sole and heel needles knit,
a second feed at which the instep needles
knit, picks at the main feed to engage the
lower butts of the suture needles for ren-
dering the suture needle which leads the
stroke inactive, and switch cam means at the
second feed to engage the upper butts of the
95 suture needles for throwing the trailing suture
needle down to active position to knit,
each suture needle knitting only once on
each stroke, both suture needles dealing only
with single loops which are interknit in
100 making the seam, substantially as described.

22. A split foot stocking machine having
a main feed and a second feed, the stitch
cams of both feeds being at the same level
suture needles of like formation, each hav-
ing upper and lower butts, narrowing picks
at said level for heel and toe work, and for
rendering each of the suture needles inop-
erative and operative alternately at the main
feed as to stitch formation and means at the
second feed acting on the upper butts for
rendering each suture needle operative and
inoperative as to stitch formation alternately
110 at the said second feed, both suture
needles dealing only with single loops sub-
stantially as described. 115

23. A split foot stocking machine having
a main feed and a second feed, the stitch
cams of both feeds being at the same level,
narrowing picks at said level for heel and
toe work, and for rendering each of the suture
needles inoperative and operative alter-
nately at the main feed as to stitch forma-
tion and means at the second feed for ren-
dering each suture needle operative and in-
operative as to stitch formation alternately
125 at the said second feed, said last named 130

means consisting of a pair of adjacent alternately acting switch cams which for rendering the suture needles operative throw them down into range of the stitch cams of the second set, both suture needles dealing only with single loops substantially as described.

24. In combination in a split foot stocking machine, a main feed having cams, a supplemental feed having cams, instep needles having upper and lower butts, suture needles having lower butts and having upper butts shorter than the upper butts of the instep needles, heel and toe needles having only lower butts, narrowing picks at the main cams, widening pick means, at the supplemental feed, instep cam means elevated in respect to the main and supplemental cams for controlling the instep needles, and a pair of switch cams for controlling the instep and suture needles, said switch cams being elevated in respect to the main and supplemental cams, one of said cams lowering the instep and the trailing suture needle to the supplemental stitch cam, on one stroke and the other cam lowering the instep needles and the trailing suture needle on the other stroke, said cams being interconnected so that each when operated will set the other in position for lowering the said instep and trailing suture needle, said cams being initially controlled alternately by contact of the upper butts of the instep needles therewith, substantially as described.

25. In combination in a split foot stocking machine, instep needles and suture needles having lower butts, stitch cams for acting upon said butts, the said instep needles having upper butts and the suture needles having upper butts shorter than those of the instep needles, and a pair of switch cams for throwing the instep needles and suture needles downward to be acted on by the cams first mentioned, said switch cams being interconnected so that each when operated will set the other in position for missing the leading suture needle and for lowering the instep and trailing suture needle, said cams being initially operated alternately by contact of the upper butts of the instep needles therewith.

26. In combination in a split foot stocking machine, heel and toe needles, instep needles, a suture needle at each side of the needle circle interposed between the series of heel and toe needles and the series of instep needles, main and supplemental stitch cams, and a pair of switch cams at the supplemental stitch cams, interconnected and each positioned by the action of the butts of the instep needles, on the companion cam, to miss the leading suture needle, and lower the instep needles and the trailing suture needle, whereby the said leading suture needle will not knit and the instep and trailing

suture needle will knit, substantially as described.

27. In combination in a split foot stocking machine, heel and toe needles, instep needles, a suture needle at each side of the needle circle interposed between the series of heel and toe needles, and the series of instep needles, main and supplemental feeds with stitch cams at each feed, and cam means controlled by contact of the butts of the instep needles therewith for missing the leading suture needle to eliminate its knitting function and for lowering the instep needles and the trailing suture needle to the stitch cams for knitting, substantially as described.

28. In combination in a split foot stocking machine, short butt suture needles, longer butt instep needles, stitch cams, and down throw switch cams to depress the suture needles, into line with their stitch cams, said cams being interconnected with a degree of lost motion whereby on one stroke one cam will be fully retracted by the longer butt instep needles contacting therewith, which through the lost motion connection will retract the other cam part way to allow the short butt suture needles to pass without deflection, but into position to throw down the instep needles to make stitches, the said cams, when the trailing suture needle comes around, operating so that the fully retracted one of these cams will snap in step by step, first off of the trailing longer butt instep needle and then off of the adjacent trailing short butt suture needle to thereby set the companion cam all the way in to depress said trailing suture needle to its stitch cam for forming a loop thereon.

29. In combination in a split foot stocking machine, heel and toe needles, instep needles having upper butts, suture needles having upper shorter butts, all said needles having lower butts, instep cams occupying a position to act on the upper butts of the instep needles but to miss the short butts of the suture needles and a main and a second set of stitch cams to cooperate with the lower butts of the needles, substantially as described.

30. In combination in a split foot stocking knitting machine, heel and toe needles, instep needles and suture needles, all of said needles having lower butts of one height, the instep needles having upper butts of substantially the same length as the lower butts, the suture needles having short upper butts and the heel and toe needles having no upper butts, a set of knitting cams and narrowing picks at the main feed, a set of knitting cams and widening pick mechanism at a second feed, said cams and picks being at one level to act on the lower butts of the needles, said narrowing picks operating upon the lower butts of the suture needles

to raise them to idle position alternately in oscillating knitting, and allowing them to knit alternately in said oscillating knitting, an instep raising cam to act on the upper butts of the instep needles, but not on the butts of the suture needles, an instep lowering cam, and switch cams at the second feed to throw down the short butt suture needles to engage the stitch cams of

10 the second feed when either of said needles trails a series of needles which knit, and to allow said short butt suture needles to pass without forming a stitch when they are the leading needles of a knitting series, substantially as described.

31. In combination in a split foot stocking knitting machine, heel and toe, instep and suture needles, knitting cams for said needles arranged in a main and second set, said suture needles having butts shorter than the butts of the instep needles, a pair of switch cams movable towards and from the needle cylinder, means connecting the cams whereby movement of one a full stroke away from the path of the needle butts will give a partial outward movement to the other cam, to allow the leading short butt needle to pass and miss knitting but to throw down the longer butt instep needles for knitting, the right hand cam being given a full re- 85

25 retracing movement by contact of the longer butt needles on the stroke of the needle cylinder to the left and the left hand cam being given a full

30 movement by said longer butt needles on the stroke to the right, each of said fully

35 retracted cams snapping off of the butts of the trailing needles to allow the other cam to be set in across the path of the trailing short butt suture needle for throwing the

40 same into engagement with the stitch cam, substantially as described.

32. In combination in a split foot stocking knitting machine, heel and toe, instep and suture needles, knitting cams for said

45 needles arranged in a main and second set, said suture needles having butts shorter than the butts of the instep needles, a pair of switch cams movable towards and from the needle cylinder, means connecting the cams,

50 whereby movement of one a full stroke away from the path of the needle butts will give a partial outward movement to the other cam to allow the leading short butt needle to pass and miss knitting but to throw down

55 the longer butt instep needles for knitting, the right hand cam being given a full re-

60 tracting movement by contact of the longer butt needles on the stroke of the needle cylinder to the left and the left hand cam being

65 given a full movement by said longer butt needles on the stroke to the right, each of said fully retracted cams snapping off of the butts of the trailing needles, to allow the

70 other cam to be set in across the path of the trailing short butt suture needle for throw-

ing the same into engagement with the stitch cam, each of said cams having inclined inner faces to receive contact of the longer butt needles whereby said cams will be retracted, substantially as described.

33. In combination in a split foot stocking knitting machine, heel and toe, instep and suture needles, knitting cams for said needles arranged in a main and second set, said suture needles having butts shorter than the butts of the instep needles, a pair of switch cams movable towards and from the needle cylinder, means connecting the cams whereby movement of one a full stroke away from the path of the needle butts will give a partial outward movement to the other cam, to allow the leading short butt needle to pass and miss knitting but to throw down the longer butt instep needles for knitting, the right hand cam being given a full re- 85

75 retracing movement by contact of the longer butt needles on the stroke of the needle cylinder to the left and the left hand cam being given a full movement by said longer

80 butts needles on the stroke to the right, each of said fully retracted cams snapping off of the butts of the trailing needles to allow the other cam to be set in across the path of the trailing short butt suture needle for throw-

85 ing the same into engagement with the stitch cam, the said connection between the cams consisting of a slide having notches receiving pins on the cams of smaller diameter than the notches, substantially as described.

34. In combination in a split foot stocking 100 knitting machine, heel and toe, instep and suture needles, the latter having short upper butts shorter than upper butts of the instep needles, all the needles having lower butts, a main and a second set of knitting cams co- 105

operating with the lower butts, and a pair of switch cams for cooperating with the upper butts, said switch cams being mounted on

110 horizontally swinging arms and means connecting the switch cams to cause the last cam passed according to the direction of the

stroke in oscillating knitting to operate the longer butt instep needles while missing the leading short butt suture needle, but to operate the short butt trailing needle.

35. In combination in a split foot stocking knitting machine, heel and toe, instep and suture needles, the latter having short upper butts shorter than upper butts of the instep needles, all the needles having lower butts, a main and a second set of knitting cams

115

cooperating with the lower butts, and a pair of switch cams for cooperating with the upper butts, said switch cams being mounted on horizontally swinging arms and means

120 connecting the switch cams to cause the last cam passed according to the direction of the

stroke in oscillating knitting to operate the longer butt instep needles while missing the leading short butt suture needle, but to op-

130

erate the short butt trailing needle, and a split collar surrounding the needle cylinder to afford a bearing therefor and to hold the needles or jacks, the sections of said collar being pivotally mounted at one end and having locking means at their opposite ends.

36. In combination in a split foot stocking knitting machine, instep needles having upper and lower butts, heel and toe needles having lower butts and suture needles having upper butts shorter than the upper butts of the instep needles, needle cams and picks cooperating with the lower butts of all the needles, a pair of switch cams cooperating with the upper butts of the instep and suture needles, said cams being movable towards and from the needle cylinder and controlled by contact of the upper butts of the needles, and means including pattern mechanism for automatically controlling both switch cams to set them in operative or inoperative position, substantially as described.

37. In combination in a split foot stocking knitting machine, instep needles having upper and lower butts, heel and toe needles having lower butts and suture needles having upper butts shorter than the upper butts of the instep needles, needle cams and picks cooperating with the lower butts of all the needles, a pair of switch cams cooperating with the upper butts of the instep and suture needles; said cams being movable towards and from the needle cylinder and controlled by contact of the upper butts of the needles and means including pattern mechanism for automatically controlling both switch cams to set them in operative or inoperative position, said means also including a connection between the two cams by which both are simultaneously operated or one is allowed to move in advance of the other under contact with the butts of the needles, substantially as described.

38. In combination in a split fabric stocking machine, a main yarn feed with a cam set for making the sole and heel and the portion above the heel, a second yarn feed for the instep yarn having a cam set for making the instep and the portion at the front of the angle, a movable yarn guide at the second feed, operating means for positioning said guide at the outside of the needle row for feeding yarn to the needles, and for moving the yarn guide to locate the instep yarn in idle position inside of the needle row while the heel pocket is formed, cutter and clamp means within the needle

circle, means to deflect the idle yarn away from said cutter and clamp so that it will remain tied into the fabric, said operating means restoring the instep yarn guide to active position outside the needle row and in advance of the trailing end of the series of heel and toe needles to be knit into the fabric for several needles with the main 65 yarn, said instep yarn guide maintaining its active position while the front ankle portion of the stocking is knit, together with the knitting of the rear ankle portion at the main feed, said operating means then 70 moving the instep yarn guide to idle position with the yarn laid under the beards of several needles which knit the instep yarn into the fabric at the main feed together with the main yarn, said deflecting means 75 then directing the yarn to the clamp and cutter, substantially as described.

39. The herein-described process of knitting a split foot stocking, comprising knitting the sole with a yarn at the main feed 80 and the instep with a yarn at a second feed diametrically opposite the first, lifting the instep yarn from feeding position when knitting the heel, but leaving it tied to the fabric at the gore, introducing the said instep yarn again and knitting a few stitches by running it in with the main yarn, then knitting the front of the stocking above the instep while the portion above the heel is being knit with yarn from the main feed, 90 and severing the instep yarn after knitting it in with said other yarn at its point of termination in the fabric.

40. The herein-described process of knitting a split foot stocking consisting in knitting the sole with a yarn from the main feed, knitting the instep with a yarn fed in at a point diametrically opposite the main feed, lifting said yarn from work while maintaining it tied into the fabric, knitting the heel, then introducing the instep yarn again by throwing its yarn guide to the outside of the needle row, and allowing the yarn to wrap around the outside of the needle row after passing out between the needles and knitting this yarn in with yarn from the main feed for a few stitches and then resuming split fabric knitting above the instep and heel, substantially as described.

In testimony whereof, I affix my signature.

GEORGE LAWSON BALLARD.
